THIEVING LIQUID SAMPLER

John S. Porter, Escondido, Calif.

Application June 12, 1957, Serial No. 665,276

3 Claims. (Cl. 73—425.4)

The present invention relates generally to means for checking and sampling liquid, and more particularly to a liquid sampler with special means for thieving a sample at a given depth and for dumping this sample when such dumping is desired.

The primary object of this invention is to provide a liquid sampler which can be lowered to a given depth in the liquid and then opened to secure the required quantity of the liquid at that particular depth, without danger of the core or sample becoming mixed with liquid at a different depth.

Another object of this invention is to provide a liquid sampler wherein the necessary valve opening is accomplished by a mere manual jerking of the sampling tube, whereafter the sample can be raised and inspected or retained for analysis, or simply returned to the tank by a simple manipulation of the apparatus.

Another object of this invention is to provide an attachment for a liquid sampler of the type disclosed in my Patent No. 2,751,787, whereby the sampler of the patent is adapted for thieving operation.

Still another object of this invention, ancillary to the immediately preceding object, is to provide such an attachment as can be easily carried in the pocket of an operator and incorporated into the liquid sample only when required, thus making for optimum convenience of operation.

Yet another object of this invention is to provide such an attachment as requires absolutely no change whatever in the liquid sampler as used for operations other than securing of samples restricted to particular depths. In other words when a core or sample for disclosing stratification, presence of condensation water, and the like, is desired the said attachment simply is not used.

With these objects definitely in view, along with other objects which will appear hereinafter as this description proceeds, this invention resides in the novel construction, combination and arrangement of elements and portions as will be hereinafter fully described in the specification, particularly pointed out in the claims, and illustrated in the drawing which forms a material part of this disclosure and in which:

Figure 1 is an isometric view of the closure member constituting the attachment for thieving;

Figure 2 is a side elevational view of said attachment;

Figure 3 is a vertical, central sectional view of said attachment;

Figure 4 is a side elevational view of a liquid sampler valve assembly, with a sampling tube and measuring tape shown fragmentarily, and showing the said closure member as the same in manually placing on the lower end of the valve assembly to close the end of the valve while the sampling tube and valve assembly are being lowered to the depth at which the sample is to be thieved;

Figure 5 is a view similar to Figure 4 and showing the closure member in a second position thereof, the result of a quick jerk on the sampling tube, in which second

2

position the closure member prevents the valve operator from holding the valve open; and

Figure 6 is a vertical, central sectional view of the structure shown in Figure 5 with the closure member shown in side elevation as from the right hand side of Figure 5 and with the upper, forward portion of this closure member broken away to disclose the structure of the valve operator.

Similar characters of reference indicate similar or identical elements and portions throughout the specification and the drawing.

Referring now to the drawing in detail this invention includes a sampling tube 10, preferably of transparent plastic material, the lower end only thereof being shown and this lower end is permanently secured to a hollow element 12 of the tubular or sleeve form, by means of a transverse pin 14 extending through both tube and hollow element. A flexible, metal measuring tape 16 extends throughout the length of the tube 10, the lower end portion only being illustrated, and this lower end is also secured relative to the tube 10 and element 12 by the pin 14.

The hollow element 12 has a fluid inlet 18 in what may be considered its lower end and a simple valve 20 closes the inlet 18 under the force of gravity acting on the valve itself and on fluid entrapped in the tube 10, until such time as the pressure differential is such as to open this valve. The operation of this valve, or one extremely similar thereto, is fully disclosed in my said Patent No. 2,751,787. A yoke 24, generally U-shaped, is pivoted on the lower end portion of an inertia element by means of opposed, outwardly extending trunnions 26.

The closure member, generally indicated by the numeral 28, defines a cup between an upstanding, annular flange 30 and a plate-like body portion 32 as best illustrated in Figure 1. Slits 34 are provided in the upstanding flange 30, and since the closure member will ordinarily be constructed of plastic which is somewhat resilient, the slits 34 permit the tight engagement of the closure member on the lower end of the hollow element 12, by mere manual pressing of the closure member on to the member 12 to assume the position illustrated in Figure 4. In this position the inlet 18 is completely closed. The apparatus is now conditioned for being lowered to the desired depth at which a sample of the liquid is to be thieved. To accomplish this, the operator gives the sampling tube 10 a sharp vertical jerk and the inertia element 22 moves downwardly relative to the hollow element 12, carrying with it the yoke 24 and the closure member 28, thus opening the inlet 18 and the fluid is free to flow into the sampling tube.

Provision must be made to prevent escape of this fluid as the tube is raised and provision must also be made to prevent liquid at other depth from entering the tube. This is accomplished in the following manner. The lugs 36 on the closure member 28 are provided with opposed keyhole slots 38 which receive bight portions of the yoke 24 and the closure member is thus made free to pivot into the position indicated in Figure 5 when the inertia member 22 is shifted as aforesaid. In other words, the closure member 28 is acted upon by the force of gravity and also affected by the resistance of the liquid and will ordinarily assume a position either identical with that shown in Figure 5 or at least some position other than that shown in Figure 4 when the inertia member is returned upwardly by the spring 40, which spring is compressed between the upper end of the hollow element 12 and an inner shoulder 42 on the upper end of the inertia member 22, externally and coaxially of the tube 10. In this position the closure member 28 prevents the valve operator 44, and inwardly bent central portion of the bight portion of the yoke 24, from entering the inlet 18.

and unseating the valve 20. Actually the closure member in this position can better be thought of as merely making the valve operator 44 inoperative, with the result that, when the tube and valve are raised, the valve 20 remains closed and retains the sample.

Having inspected the sample or having secured the required amount thereof for analysis or the like, the operator will now desire to dump the sample or the remains thereof back into the tank. This is accomplished simply and easily by the mere removal of the closure member from the yoke 24, and allowing the valve operator 44 to unseat the valve 20, the tube being lowered sufficiently to allow substantially complete draining thereof. In this respect, it may be noted that the yoke 24 is of resilient material and the arms thereof are urged radially outwardly into engagement with the inner bore face 46 at the lower end of the inertia member 22, this obviously resulting in the biasing of the yoke toward axial alignment with the inertia 22, and the valve operator 44 is thus aligned with the inlet 18 and valve 20.

While this invention and the entire foregoing specification is primarily concerned with the provision of means for thieving a liquid sample and returning the sample to the tank, it may be noted that the structure disclosed in Figure 6 with the closure member 28 removed can be used, essentially according to the teaching in my Patent No. 2,751,787, for the securing of core samples in the ordinary manner. To do this, the yoke 24 is merely retracted into an oblique position with the valve operator resting on the exterior curved surface at the lower end of the hollow element 12. The tube can then be lowered, usually completely to the bottom of the tank, the valve 20 being free to open as the result of the differential in pressure and, of course, immediately closing to retain the core sample when the tube is raised. To dump this core sample, the tube is lowered again to the same level and a quick jerk will cause the inertia element 22 to be moved relative to the hollow element 12, releasing the yoke from its engagement on the side of the hollow element and, as before described, the resilient yoke is biased by the action of the inner bore face 46 into alignment with the inlet 18 and as a result, when the inertia member is returned by the spring 40, the valve operator 44 opens the valve 20 and dumps the core sample, retaining the valve open as the tube is raised and emptied. The disclosure in this paragraph, it is repeated, does not relate to the thieving operation and is included here in order that there be no question as to the complete disclosure of the present improvements in my device.

The operation of this invention has already been detailed in this connection with the foregoing description of the physical embodiment of the invention and it is believed that no further discussion of the operation is required.

Minor variations of the disclosed embodiment may be resorted to without departure from the spirit and scope of this invention. For example, the specific shape of the closure member 28 can be varied materially without any corresponding significant change in its functioning, the essential features being probably the provision of some element, cup or cap to close the inlet 18, means to hold the valve operator 44 in inoperative position as indicated

in Figures 5 and 6. It is conceived that this closure member can be shifted to a third position while still remaining on the valve assembly although it is completely inoperative in this third position, such an embodiment possibly entailing the shifting of the keyhole slot 38, or its equivalent, so that the closure member can be attached to the side of the yoke 24. Still other means could be employed, all within the general concept of this invention, and the foregoing specification and drawing should be considered as illustrative rather than limited.

I claim:

1. A liquid sampler comprising: a sampling tube; a valve assembly including a hollow element on one end of said tube, there being an inlet in said element, a valve normally closing said inlet, an inertia element slidably mounted on said element, a spring biasing said inertia element to move in one direction; a valve opener carried by said inertia element; a member closing said inlet in one position of the member to prevent entry of liquid into the tube during the lowering of the tube into a liquid

in the first part of a thieving operation; said member being connected to said inertia element to be shifted to uncover the inlet when said elements are relatively shifted, to a second position holding said valve opener in inoperative position to retain fluid in the tube while being raised; and said member being easily removable making said valve opener operational for dumping the measured liquid from the tube.

2. A liquid sampler according to claim 1 wherein said elements are coaxial; said spring being compressed between one end of said hollow element and a portion of said inertia element; said inlet being axial of the other end of said hollow element; said valve opener being a resilient yoke having opposed trunnion terminals pivoted on said inertia element, a valve engaging portion at the center of said yoke, and opposed arms bearing against an axial bore portion of said inertia element so that said valve engaging portion is biased toward alignment with said inlet and valve; said member being a cap pivotally and removably secured on said yoke.

3. The combination in a thieving liquid sampler comprising a sampling tube; a one-way valve assembly having an inlet at one end of the tube and a valve closing said inlet; an inertia element operatively connected to said valve assembly and having a valve opener holding said valve open in one position of inertia element; closure means distinct from said valve to close said inlet; said closure means also constituting, in a second position thereof, as means rendering said opener and said closure means temporarily inoperative; said closure means being easily removable making said valve opener operational for dumping a fluid sample from said tube, said valve opener being a yoke carried by said inertia element, and said closure means being a cup member pivotally mounted on said yoke.
